UNITED STATES PATENT OFFICE.

GEORGE W. ZABEL, OF SHERMAN, CALIFORNIA.

HINGE.

Application filed August 25, 1926. Serial No. 131,415.

This invention relates to casement window hinges, and more especially to a device which is attachable to the wings or leaves of such hinges for the purpose of frictionally but firmly securing the swinging window at any desired angle within its limit of movement.

An object is to provide a friction unit readily applicable to such type of hinges with little or no change in the construction thereof.

Another object is to provide a friction unit with means to apply readily on the usual leaves so that the swinging leaf may have the usual movement and will rest firmly at the adjusted angle.

A further object is to provide a friction unit so interlockable with the hinge that the unit can be removed only, but easily, at one position of the hinge leaves.

20 A still further object is to provide a friction unit including a hinge pintle substitutable for the usual hinge pin and having friction members engaging, immovably, relative stock leaves of the hinge without in any way altering the leaves, so that the present holding unit may be applied to stock or to installed hinges of standard type without discarding stock or removing hung hinges.

30 The invention is not limited in its objects to those above enumerated, and other purposes, features and advantages will be made manifest in the following specification of the embodiments illustrated herewith; it being reserved and understood that modifications, variations and adaptations may be resorted to within the spirit and principle of the invention as it is here claimed.

Sheet I illustrates an embodiment of the apparatus, wherein—

Figure 1 is a side elevation of the complete friction unit.

Figure 2 is a top plan view of the unit; hinge leaves being indicated, by dotted lines, in position for application of the unit.

Figure 3 is a sectional view of the unit friction members.

Figure 4 is a plan of the blank of the two-plate friction member.

50 Figure 5 is a plan of the intermediate friction disk.

Figure 6 is a front elevation of an open hinge; showing the friction parts in section and interlocked to the hinge, and

55 Figure 7 is a plan of the open hinge.

Sheet II illustrates an embodiment, wherein—

Figure 8 is a top plan of the hinge and its holding unit.

Figure 9 is an elevation of the hinge and the unit applied thereto.

Figure 10 is an elevation and section of leaves at 90° apart.

Figure 11 is an edge view of one leaf and its interlocked friction disk.

Figure 12 is an elevation of the unit, apart from its hinge.

Figure 13 is a plan of the two-plate member.

Figure 14 is a plan of the hooking disc.

In Figs. 1 to 7 a form of the invention is shown wherein the friction unit is designed to interlock with one leaf A of the hinge, which is shown as being provided at its top with a notch or recess a under a horn a^1 . The companion leaf B has its journal b cut down from the top and at a point just opposite the horn a^1 it has an angle recess b^1 . This is the only difference from the stock leaves of such hinges, which usually have a removable pivot pin.

The interlocking friction unit comprises a pintle 3 with a small shoulder 4 and a screw-threaded end 5 on which is turnable a clamp nut 6 having a cross-slot 7 for a screw-driver or other suitable implement. Preferably the head of the screw end 5 is buried over so as to prevent the nut from being run off.

Fixed on the pintle and setting against the shoulder 4 is a lower friction plate 10 joined by a tie or loop 11 to an upper plate 12. These plates are spaced axially to receive a turnable, intermediate friction disk 14. The lower plate 10 has a notch 10^a , slightly tangential to its axis, to receive the corner b^2 of the leaf B so that the plates 10—12 are engaged to the leaf B against relative movement. The recess b^1 just clears the edge of the middle disk 14, which has a notch 14^a to receive the horn a^1 of the leaf to interconnect these parts.

The plates 10—12 and the disk 14 have rim-marks 16, Fig. 1, and when these are in alignment notch 14^a , of disk 14, registers over a clearance slot 10^b in the edge of plate 10. When in such relation the friction unit is dropped into place on the top of the properly angled leaves A—B (Fig. 2); leaf B passing into notch 10^a and horn a^1 passing

up into notch 14^a, and pintle 3 fitting into the leaf journals.

When so assembled, if the leaves are now opened out the disk 14 turns and the horn 5 ^a passes away from the clearance slot 10^b, which results in interlocking the unit in place so that it cannot be pulled axially from the hinge, which, obviously, is an important advantage. Another advantage is 10 that the friction adjusting nut 6 cannot be run off the unit and lost. The unit is a self-contained device including the pintle 3, plates 10—12, disk 14, and nut 6, attachable to and detachable, from the hinge leaves, 15 as a whole.

One or more of the friction hinges may be used in hanging a window, or other swinging structure, and by means of the nut 6 the frictional resistance against movement 20 of the swinging part may be easily regulated. It will be noted that no loosening tendency is transmitted to the nut when the leaves are relatively turned.

A very simple and practical form of the 25 invention is shown in Figs. 8 to 14, wherein a stock hinge includes leaves A and B with the usual pin journals C. The hinge pin is removed and in its place is substituted a long pintle 3 whose lower end is threaded 30 to receive a nut 6. The pintle passes freely through a lower plate 20 and is fixed to a head plate 22 connected to plate 20 by a tie loop 21. This loop is struck down to form a side shoulder 21^a below the plate 20 and to engage the side of leaf B as seen in Fig. 35 10. Adjacent to the shoulder 21^a there is a tangential kerf 21^b and a tongue 21^c is punched down so as to engage against the near face of the leaf B, which is, therefore, 40 retained between shoulder 21^a and tongue 21^c. This holds the leaf B as to the pintle.

Turnable between the plates 20—22 is a 45 disk 24, on the pintle 3, having a lateral, down-turned yoke 24^a the slot 24^b of which is tangential to the axis of the disk. By swinging the yoke around as to the loop 21 until the side of the yoke hits the loop, the slot 24^b and the tongue 21^c will readily

register with the closed leaves A—B, in position shown in Fig. 8. 50

The pintle 3 is secured in place by application of nut 6 to its lower end. When the plates and the disk have been hooked onto the leaves A—B the nut is tightened up as desired and so obtain plate friction on the 55 disk to hold the swinging leaf at the desired angle.

The advantage of this form of hinge clamp is that it can be applied without altering the hinge leaves in any manner. 60

What is claimed is:

1. A friction clamp for hinges including a pintle for the hinge leaves, spaced clamp plates one of which is rigid on the pintle and the other being movable, a friction member between the plates and turnable on the pintle, and means for closing the plates against the member; said plates immovably engaging one leaf and the member immovably engaging the other leaf. 70

2. A friction unit for hinges, including a pintle for the leaves, clamp plates secured non-rotatively on the pintle, a friction member grippable between the plates, said member and plates being attachable to respective 75 leaves, and means for holding the unit inseparable on the leaves except at one position thereof.

3. A friction clamp for hinges, including a pin body insertable into a hub of one of 80 the leaves and being non-turnable relative thereto, spaced clamp plates non-rotatively combined with the pin body, a friction member rotative between the plates and interlocking with the other leaf, and means for closing the plates against the said member. 85

4. A friction clamp for hinges, including a pin for the hinge leaves, spaced clamp plates yieldably connected by a bar loop and 90 non-rotative on the pin, said loop interlocking with one leaf, a rotative disk between the plates and interlocking with the other leaf, and a nut on the pin for closing the plates against the disk. 90

GEORGE W. ZABEL.
